(57) **CLAIM**

The ornamental design for the cartridge, as shown and described.

DESCRIPTION

FIG. 1 is a perspective view of my new design, the base being shown in dashed lines;

FIG. 2 is the side view of the design of FIG. 1 with the base being shown in dashed lines, the side views of the design having six-axis symmetry;

FIG. 3 is the top view of the design of FIGS. 1 and 2; and, FIG. 4 is the bottom view of the design of FIGS. 1-3, with the base not being part of the design.

The broken view of the design indicates that it is not limited to a particular length.

The broken line showing of the portion of the base is for illustrative purposes only and forms no part of the claimed design.
